UNITED STATES PATENT OFFICE.

RICHARD WALTER WHITE, OF ROCHESTER, NEW YORK, ASSIGNOR TO LAWYERS CO-OPERATIVE PUBLISHING CO., OF ROCHESTER, NEW YORK, A CORPORATION OF NEW YORK.

HOLDER FOR THE BINDINGS OF BOOKS FOR SUPPLEMENTAL SHEETS.

Application filed April 25, 1928. Serial No. 272,783.

The object of this invention is to provide a new and improved holder for the bindings of books so that supplemental sheets may be added to the book from time to time and 5 made practically a permanent part of the book, the holder permitting these supplemental sheets to be readily attached to and detached from the binding of the book.

This and other objects of the invention 10 will be illustrated in the drawing, described in the specification and pointed out in the claims at the end thereof.

In the drawings:

Figure 1 is a perspective view of a book 15 to one of the covers of which my improvement has been added, the cover of the book being shown open.

Figure 2 is a section on the line 2^x, 2^x of Figure 1.

Figure 3 is a detail view of the supplement 20 of sheets as they will be made to be attached to the book cover shown in Figure 1.

Figure 4 is an enlargement of the upper 25 portion of the book cover shown in Figure 1, the cover being partly broken away so as to show the pocket and the cover back of it in section.

Figure 5 is an enlargement of a modified 30 form of the upper portion of the book cover in which the cloth covering material is folded over at the top with a wide margin to form the pocket for holding the backing of the supplemental sheets, the cover being partly broken away to show the assembly of the 35 parts.

In the drawings like reference numerals indicate like parts.

Books of reference when printed and bound in the usual way get out of date sooner 40 or later, and in such case it is desirable to provide some means by which the book can be kept up to date by the addition of extra printed pages thereto. The binding of books is usually sewed and fastened together in a way that does not permit the taking of it apart for the purpose of adding pages thereto. Therefore, it is desirable to provide means by which extra supplemental pages may be added to a book without disturbing the binding thereof, and yet make the supplemental pages an integral part of the book.

For this purpose I bind the book in the ordinary way. That is, sew the leaves together and attach the leaves so assembled and 55 sewed to the cover in the usual way. The invention lies more especially in the cover of the book in which reference numeral 1 indicates the board of the cover.

Along the upper edge of the board of the 60 cover I paste a reinforcing strip 2, which reinforcing strip is not attached to the board in the intermediate section thereof between the dotted lines 3 and 4 but is attached to the board at both ends on the outside of said 65 dotted lines. The covering cloth 5 is then fastened to the outside of the board 1 of the cover by glue or paste as may be desired and the margin thereof is turned over the upper edge of the board. This margin of the cloth 70 more or less overlaps the reinforcing strip 2, and is firmly pasted or glued thereto. The fly sheet 7 is then pasted on the inside of the board completely covering the board from the top to the bottom thereof and overlapping both the reinforcing strip 2 and the margin of the cloth covering material 5. I then cut the fly sheet 7 along the lower edge 75 of the reinforcing strip 2 between the dotted lines 3 and 4 and as the reinforcing strip 2 so has not been fastened to the board of the cover along this line a pocket is left thereby, which opens along the cut line. The lower edge of the cover is formed in the same way to make a pocket, both pockets on the board 80 appearing at the top and bottom of Fig. 2.

In Figure 5 I form the upper and lower edge of the cover in the same way except that the cloth 5 is extended down to the lower edge of the reinforcing strip 2 thereby making the 90 reinforcing strip just that much stronger. The fly sheet 7 covers the board 1 of the cover together with the cloth covering material 5 that has been turned over the edge of the cover but in both cases a strip of material 2 is 95 interposed between the cloth fabric and the fly sheet on the one side, and the board 1 of the cover on the other side so that these parts will not be pasted directly to the board of the cover but will be left detached far enough 100 along the upper and lower margin of the cover to form a pocket for the reception of the backing of the supplemental sheets.

The supplemental sheets 11 are fastened to-

gether in any way that may be desired as for example by stapling and to the supplement so formed is also fastened the backing card 12 which is of standard form and size, and is made with reference to the pockets above described to be used in said pockets. For this purpose the backing card is cut away to form shoulders at 13 and 14 from which the backing card extends up and down to points 15 and 16. The backing card then tapers forward to the corners 17 and 18. The forward edge 19 of the backing card is substantially parallel with the rear edge 20. This backing card is always fastened to the supplemental sheets preferably by the publisher and the owner of the book inserts the upper corner 15 into the upper pocket and the lower corner 16 into the lower pocket, the upper and lower edges of the card easily following the corners into place in the pockets and thus make positive engagement therewith. The portions of the backing card above the shoulder 13 and below the shoulder 14 make an ample engagement with the pockets at the top and bottom of the cover so as to firmly hold the supplement in engagement therewith. The backing card is sprung for the purpose of making the ends thereof engage with the pockets in the cover, but when the backing card is in engagement with the pockets it flattens out and pushes the ends into the pockets and holds the supplement firmly to the cover. The backing card to secure this result is made preferably of stiff material such as tag board.

I claim:

1. A binding for a book and supplement therefor comprising a cover and pockets at the top and bottom of said cover, said pockets opening toward the middle of the cover, a supplement for said book comprising a plurality of pages with a backing card therefor, the upper and lower ends of said card being

adapted to engage in said pockets to hold the supplement in place. 45

2. A binding for a book and supplement therefor comprising a cover and pockets at the top and bottom of said cover, said pockets opening toward the middle of the cover, a supplement for said book comprising a plurality of pages with a backing card therefor, the upper and lower ends of said card being adapted to engage in said pockets to hold the supplement in place, said backing card having its corners at the rear edge cut away to 55 reduce the width of the backing card where it enters the pockets.

3. A binding for a book and supplement therefor comprising a cover, a strip extending along the top and bottom of the inside 60 of the cover, the ends of the strip being pasted thereto, the intermediate part of the strip being left loose therefrom to form pockets at the top and bottom of the cover.

4. A binding for a book and supplement therefor comprising a cover and strips extending along the top and bottom of the inside of the cover, the ends of the strips being pasted thereto to form pockets at the top 70 and bottom of said cover, said pockets opening toward the middle of the cover, a supplement for said book comprising a plurality of pages with a backing card therefor, the upper and lower ends of said card being 75 adapted to engage in said pockets to hold the supplement in place, a covering cloth for said cover, said cloth overlapping said strip and reinforcing it, a fly sheet pasted over the inside of the cover and overlapping said strip 80 and said covering cloth, said sheet being slit along the inner edges of the loose portions of the strips to uncover the pockets formed by the strips.

In testimony whereof I affix my signature.

RICHARD WALTER WHITE.
